UNITED STATES PATENT OFFICE.

EDWARD GARRETT, OF NEW ORLEANS, LOUISIANA.

IMPROVEMENT IN TIES FOR COTTON-BALES.

Specification forming part of Letters Patent No. 24,112, dated May 24, 1859.

To all whom it may concern:

Be it known that I, EDWARD GARRETT, of the city of New Orleans, State of Louisiana, have made a new and useful Improvement in Ties of Iron Bands for Cotton-Bales; and I hereby declare the following to be a full, clear, and exact description thereof, reference being had to the accompanying drawings, and to the letters of reference marked thereon, making a part of this specification, the same letters being used to designate the same parts shown in the respective figures.

Figure 1 is a side or top view. Fig. 2 is an edge view taken from line X in Fig. 1, which is sectional in part.

The ends of the band are marked A and B, and both pass through the mortise *o* in plate *a*. This plate has two mortises, marked, respectively, *o* and *i*. The end A is first passed through mortise *o*, then through *i*, as seen by Fig. 2, which makes the permanent fastening of end A to plate *a*. The changes to be made in the length of the band are effected through end B. Prior to this end being passed through mortise *o* the plate *c*, having mortise *s*, is placed

on this end, and after the end has been passed through mortise *o* it is drawn back, which forms a hook, and again passed through mortise *s* in plate *c*, with the end below the mortise extended to increase the leverage over the band by the force of expansion of the cotton after the tie is made, which causes the band to be bent and clamped by the sides of mortise *s*, that keeps the band from being drawn and holds it stationary. In the compressing the end B can be drawn through mortise *o*, and again passed through mortise *s*, to make the tie, as has been stated.

After this my description, what I claim as new, and desire to secure by Letters Patent, is—

The combination of the two plates *a* and *c*, when made and arranged as or substantially as has been set forth, to form a tie for iron bands for baling cotton or for similar purposes.

EDWARD GARRETT.
